S. SEGAL
KEY DUPLICATING MACHINE.
FILED DEC. 26, 1919.

By his Attorneys Samuel Segal ^{Inventor}
Jorwesend & Wecker

UNITED STATES PATENT OFFICE.

SAMUEL SEGAL, OF NEW YORK, N. Y.

KEY-DUPLICATING MACHINE.

Application filed December 26, 1919. Serial No. 347,356.

To all whom it may concern:

Be it known that I, SAMUEL SEGAL, a citizen of the United States, and a resident of New York, in the county of New York and State of New York, have invented certain new and useful Improvements in Key-Duplicating Machines, of which the following is a specification.

My invention relates to key-duplicating machines by means of which a key similar to any given master key may be easily and accurately produced or made, the invention relating more particularly to the particular form of work-holding clamps for holding the master key and key blank during the duplicating operation.

The object of my invention is the production of a work-holding clamp adapted for use on key-duplicating machines which shall be of extreme simplicity of construction and of few parts and by means of which the master key and key blank may be expeditiously placed and firmly, properly and accurately held in the desired and same relative position.

A further object of the invention is the production of a novel form of work-holding clamp for key-duplicating machines which shall be adapted to firmly hold in the desired position either a key of the cylinder lock type or a "flat" key.

Other and further objects of the invention will appear from the accompanying description, the invention consisting in the novel parts and combinations of the same hereinafter more particularly described and then specified in the claims.

In the accompanying drawing:

Fig. 1 is a plan view of a key-duplicating machine for duplicating keys of the cylinder lock type or "flat" keys.

Fig. 2 is a vertical cross-section on the line 2—2 of Fig. 1.

Fig. 3 is a plan view of my improved work-holding clamp.

Fig. 4 is a vertical cross-section on the line 4—4 of Fig. 3.

Fig. 5 is a perspective view of the sliding plate of the work-holding clamp.

Referring to the several figures of the drawing:

10 indicates the base of a key-duplicating machine which is provided with a body portion 11 having side plates 12 carrying the rod 13 connecting said side plates together.

14 indicates the carriage of the machine

which is horizontally slidably mounted on the rod 13. Said carriage is provided with the arms 15 extending outwardly therefrom and with one-piece work-holding clamp 16, 60 16' to be presently described in detail, preferably integral with said arms.

17 indicates a guiding finger which is suitably and preferably rigidly mounted in a post 18 extending upwardly from the 65 body of the machine. The outer edge of said guiding finger is bevelled as illustrated and is adapted to engage the notches in the biting edge of a cylinder lock key. 19 indicates a second guiding finger mounted in 70 a post 20 similar in construction to post 18. The outer edge of said second guiding finger is flat or squared and is adapted to engage or fit within the indentations intermediate the rectangular teeth on the biting 75 edge of a "flat" key.

21 indicates a double standard extending upwardly from the machine and having a shaft 22 journaled therein and held at one end by a suitable nut 23 and at the other 80 end by a driving wheel 24 which is provided with a handle 25 for rotating the shaft 22. The driving wheel 24 is also provided with a groove 25' adapted to receive a belt connecting with a suitable source of 85 power whereby said driving wheel may be power driven if so desired. 26 is a rotary cutting tool mounted on the shaft 22 and having a bevelled edge similar in configuration to the outer bevelled edge of the guiding finger 17. 27 indicates a rotary cutting tool of a width equal to the width of the guiding finger 19 and provided with a "saw-tooth" edge as illustrated. The distances between the centers of the clamps 16, 16', 95 the guiding finger 17 and rotary cutting tool 26 and the guiding finger 19 and rotary cutting tool 27 are preferably equal. Moreover, the outer edges or edges nearest the clamps of the guiding fingers 17 and 19 and 100 the rotary cutting tools 26 and 27 lie in the same horizontal plane.

The duplicating operation is as follows:

Assuming a key for a cylinder lock is to be duplicated, the master key is properly positioned and firmly clamped in clamp 16 and the key blank in clamp 16' with the biting edges of the key and key blank facing upwardly as shown in Fig. 1 and as will presently be explained. The wheel 24 is then 110 operated to rotate the cutting tool 26 and the carriage is swung up manually into op-

erative position on the rod 13 as shown in Fig. 1 and from its normal inoperative position as shown in Fig. 2, to cause either end of the biting edge of the master key to be pressed against the guiding finger 17. The carriage is moved slowly and horizontally along the rod 13, contact at all times being preferably kept between the biting edge of the master key and the guiding finger 17.

10 The forward movement of the carriage towards the guiding finger is limited by the depth of each notch or cut in the biting edge of the master key and a notch or cut of equal depth will be made in the edge of the key blank by the cutting tool 26 as is obvious.

15 In duplicating a flat key, the carriage is swung to the left on rod 13 until clamp 16 is in vertical alignment with the guiding finger 19 and clamp 16' with the rotary cutter 27. The master key and key blank are properly positioned and held in their respective clamps and by rotation of shaft 22 and successive engagement of the guiding finger 19 with each indentation of the master key, similar indentations are cut in the biting edge of the key blank, as will be manifest, by the cutting tool 27.

20 My improved work-holding clamps 16 and 16' for positioning and firmly holding the master key and key blank are identical in size and construction so that a description of one will suffice for both. They each comprise a one-piece ring having an enlarged head, as shown, with a slot 28 cut there-through having flat opposed surfaces, said slot forming the front jaw 29 and the rear jaw 30 of the clamp. Said rear jaw 30 is provided with a reduced or cut-out portion 31 and both jaws are provided with longitudinal parallel grooves 32 as shown. 33 indicates a flat plate engaging the reduced portion 31 of the rear jaw 30 and slidably longitudinally thereon. Said slidable plate is provided with longitudinally extending fingers 34 having inclined or toothed ends 35 and transverse grooves 36. Said fingers 34 fit and are adapted to slide within the grooves 32.

37 indicates shoulders or stops formed by 50 the reduced portion 31 and the longitudinally extending grooves 32 of the rear jaw 30 and limit the forward movement of the plate 33 in an obvious manner. The backward movement of said plate is limited by 55 a screw-threaded pin 38 provided with a head 39 and an operating thumb-piece 40, which pin is screwed into the rear jaw 30 and extends through a slot 41 with which the plate 33 is provided. The plate 33 may be 60 held in any desired position by turning the thumb-piece 40, which effects a clamping of the head 39 against the top of the plate 33. When the plate is in the extreme rear position as shown in Figs. 3 and 4, the teeth or 65 inclined ends 35 of fingers 34 extend slightly

within the slot 28, and when the plate is in the extreme forward position, the grooves 36 of fingers 34 are in register with the slot 28.

42 indicates suitable screw-threaded bolts 70 extending through the jaws 29 and 30 of the clamps 16 and 16' and which may be operated by winged heads 43 to draw said jaws together in order to clamp or hold a key therebetween when the heads are turned in one direction or to permit the jaws to spread apart due to the spring action in the metal 75 of the clamps when the heads are turned in the other direction and thereby effecting an unclamping of the key. 44 indicates suitable hooks or latches pivoted to either side 80 of the heads of the clamps.

To properly position, both transversely and longitudinally, and clamp a Yale or cylinder lock key in the clamp, assuming the jaws of the clamp are open, the plate 33 is 85 moved into the extreme rear position (see Fig. 3) with the teeth 35 thereof protruding within the slot 28. The key is then slipped between the jaws with the teeth 35 engaging the conventional groove present in the side 90 of the key. Plate 33 is then pressed or moved forwardly a distance sufficient to hold the key intermediate the ends 35 of said plate and the front jaw 29 of the clamp, but not 95 tightly clamp the same, and the plate is held in this position by turning the thumb-piece 40 to clamp the head 39 against the plate. The key may then not be withdrawn from the clamp by a vertical movement, as is obvious, but it is capable of a horizontal or longitudinal movement therein. To obtain the proper horizontal or longitudinal position of the key for the duplicating operation the latch 44 is turned up on its pivot and the 100 usual shoulder on the key adjacent the biting edge thereof is brought into close engagement with the side of the latch as shown in Figs. 1 and 2. The proper vertical or transverse and horizontal or longitudinal position of the key having thus been obtained, the 105 key is firmly clamped between the jaws of the clamp by turning the winged head 43 which also forces the plate rearwardly 110 against the action of the clamping head 39. The master key having thus been properly 115 positioned and clamped in its clamp, the key blank is also positioned and clamped in the same relative position in its clamp and the duplicating operation proceeded with as has heretofore been explained.

120 In the case of "flat" keys which are not provided with grooves in the sides thereof as are cylinder lock keys, the jaws of the clamp are opened and the plate 33 pushed forwardly until the grooves 36 are in register with slot 28 between the jaws, the plate being held in the desired position by clamping the head 39 against the plate as in the previous case. The key is then seated in the grooves 36 to obtain its proper vertical or 130

transverse position in the clamp and the proper horizontal or longitudinal position thereof is obtained by means of the latch 44, after which the key is tightly clamped between the jaws by operating the winged head 43. The key blank being also positioned and clamped in its respective clamp in the same relative position as the master key and in the same manner, the duplicating 10 operation may be proceeded with.

From the foregoing description it is apparent that the improved means on the clamp hereinbefore described for properly positioning the key in the clamp is in reality 15 a part of the clamp itself, or may be so considered, as it is unnecessary to remove it during the duplicating operation.

For properly positioning the key and key blank in their respective clamps it is necessary to fix their longitudinal and transverse 20 positions therein in the manner previously described so that the duplicating operation may be accurately effected. In the specific machine shown and described this longitudinal and transverse position is obtained by 25 adjusting the position of the key and key blank horizontally and vertically respectively but it will be understood that this is merely due to the particular organization 30 of the preferred form of machine.

What I claim as my invention is:—

1. In a key-duplicating machine, a clamp having opposed jaws adapted to grip a key and a plate carried by said clamp and adapted 35 to position the key in its proper transverse position between said jaws, said plate having a reduced end normally extending between said jaws.

2. In a key-duplicating machine, a clamp 40 having opposed jaws adapted to grip a key, means for drawing said jaws together, a 45 slideable plate carried by said clamp and lying in a plane transverse to the plane of said jaws and adapted to position the key in its proper transverse position between said 50 jaws and means for clamping said slideable plate in the desired position.

3. In a key-duplicating machine, a clamp 55 having a slotted head forming opposed jaws adapted to grip a key, said head being provided with a groove therein, means for drawing said jaws together, a slideable plate carried by said head for positioning the key between the jaws, and a finger on said slideable plate extending in the groove in said 60 head.

4. In a key-duplicating machine, a clamp 65 having opposed jaws adapted to grip a key and a plate carried by said clamp for positioning a key between the jaws, said plate being provided with means adapted to engage a groove in the side of the key.

5. In a key-duplicating machine, a clamp 70 having opposed jaws adapted to grip a key and a plate carried by said clamp for posi-

tioning a key between the jaws, said plate being provided with means adapted to engage a groove in the side of the key and with means within which the key may be seated.

6. In a key-duplicating machine, a clamp 75 having a slotted head forming opposed jaws adapted to grip a key, said head being provided with a groove therein, means for drawing said jaws together, a slideable plate carried by said head for positioning the key 80 between the jaws and a finger on said plate extending in the groove on said head and having a tooth at the end thereof and said finger being provided with a groove adapted to register with the slot in the head of the 85 clamp.

7. In a key-duplicating machine, a clamp having a slotted head forming opposed jaws adapted to grip a key, said head being provided with grooves therein, means for drawing 90 said jaws together, a slideable plate on said head for positioning the key transversely between the jaws, means for clamping said slideable plate in the desired position, fingers on said plate extending in the 95 grooves on said head, teeth on said fingers normally extending between said jaws, said fingers being also provided with grooves adapted to register with the slot in the head of the clamp and means for positioning the 100 key longitudinally between the jaws.

8. In a key-duplicating machine, a clamp having opposed jaws adapted to grip a key and means carried by said clamp adapted to support a key thereon between said jaws and 105 to engage a groove in the side of the key whereby the proper transverse position of the key in said clamp is obtained.

9. In a key-duplicating machine, a clamp having opposed jaws adapted to grip a key 110 and a plate carried by said clamp for positioning a key between the jaws of the clamp, said plate having means normally extending between said jaws and adapted to engage a groove in the side of the key.

10. In a key-duplicating machine, a clamp having opposed jaws adapted to grip a key and a plate carried by said clamp for positioning a key between the jaws, said plate being adapted to support a key thereon between said jaws and being provided with means to engage a groove in the side of the key.

11. In a key-duplicating machine, a clamp 115 comprising a one-piece ring with a slot therein forming opposed jaws and a plate carried by said clamp for positioning a key between said jaws, said plate being adapted to support a key thereon and being provided with means to engage a groove in the side of the 120 key.

12. In a key-duplicating machine, a clamp 125 having opposed jaws adapted to grip a key and provided with slideable means adapted to support a key between said jaws, said 130

means being adapted to engage a groove in the side of the key whereby the proper transverse position of the key in the clamp is obtained.

5 13. In a key-duplicating machine, a clamp having opposed jaws adapted to grip a key and means carried by and slidable on said clamp and adapted to engage a groove in the side of the key whereby the proper trans-

verse position of the key in the clamp is obtained. 10

Signed at New York in the county of New York and State of New York this 24th day of December A. D. 1919.
